CLAIM

The ornamental design for a luminaire, as shown and described.

DESCRIPTION

FIG. 1 is a front-elevational view of a first embodiment of the luminaire showing my new invention;

FIG. 2 is a rear-elevational view thereof;

FIG. 3 is a left side-elevational view thereof;

FIG. 4 is a right side-elevational view thereof;

FIG. 5 is a bottom-plan view thereof;

FIG. 6 is a top-plan view thereof;

FIG. 7 is a perspective view thereof;

FIG. 8 is a perspective view thereof in an open condition.

FIG. 9 is a front-elevational view of a second embodiment of the luminaire showing my new invention;

FIG. 10 is a rear-elevational view thereof;

FIG. 11 is a left side-elevational view thereof;

FIG. 12 is a right side-elevational view thereof;

FIG. 13 is a bottom-plan view thereof;

FIG. 14 is a top-plan view thereof;

FIG. 15 is a perspective view thereof; and,

FIG. 16 is a perspective view thereof in an open condition.

The dashed broken lines represent unclaimed LED modules and incandescent light bulbs.
